UNITED STATES PATENT OFFICE.

WALFRID GUSTAFSON, OF NEW YORK, N. Y., ASSIGNOR TO THE AMERICAN AUTOMATIC BANJO COMPANY, OF NEW JERSEY.

PICKER DEVICE FOR STRINGED MUSICAL INSTRUMENTS.

SPECIFICATION forming part of Letters Patent No. 606,207, dated June 28, 1898.

Application filed March 31, 1898. Serial No. 675,951. (No model.)

To all whom it may concern:

Be it known that I, WALFRID GUSTAFSON, a citizen of the United States of America, and a resident of New York, (Brooklyn,) in the county of Kings and State of New York, have invented certain new and useful Improvements in Picker Devices for Stringed Musical Instruments, of which the following is a specification.

10 This invention relates to apparatus for mechanically picking the strings of automatic or self-playing musical instruments, the object thereof being to provide improved means for controlling the lateral movements of the pickers, so as to compel them to follow their respective guide-cams, the latter being adapted, as is already well known, to so guide the movement of the finger as to cause it to engage with and release its string in a predetermined 15 and most effective way and to return to its first position ready for the succeeding stroke or pick by a path which carries it clear of the vibrating string. This object is secured by applying a frictional controller at one side of 20 the plane of movement of the pivot by which the picker is attached to the devices which move it longitudinally, the rubbing contact of the controller with the picker serving during the backward or string-engaging stroke 25 of the picker to hold the picker laterally toward the string against the side of its guiding-cam and serving upon the forward or return stroke of the picker to move the picker laterally away from its string, the amplitude 30 of lateral movement of the picker in each direction being determined by the guiding-cam.

Figure 1 of the drawings is a plan view, and Fig. 2 is a front view, partly in section, taken on the line 2 2 of Fig. 1, showing my improved 40 picker-controlling devices in connection with the string-picking mechanism of a mechanically-played banjo. Figs. 3 and 4 are enlarged plan views of the picker mechanism of Figs. 1 and 2, showing two different phases 45 of the movement thereof. Fig. 5 is a similar plan view showing a modified construction and arrangement of my improved picker-controller. Fig. 6 is a front view of the right-hand portion of what is shown in Fig. 5, and Fig. 7 is an end view projected from Fig. 6. Fig. 8 is a plan view, and Fig. 9 a front view,

showing a modified form of my improved picker-controller. Fig. 10 is a plan view showing still another modified form of my controller.

55

This invention, although applicable to all mechanically-operated pickers for stringed musical instruments, is illustrated herein as being used in connection with devices for picking the strings of a banjo of ordinary 60 construction. The banjo B is supported by means of the bracket 12 and posts 13, extending from the base 14. The pickers 17 are pivotally attached to their motor devices, which ordinarily and preferably consist of 65 pneumatic bellows 18, attached to the bracket 16, upon the outer ends of which is fastened the harp 15, extending over the head of the banjo and carrying the guiding-cams 21, having the apertures 22. Each picker is provided 70 with a pin or projection 23, extending into the aperture 22, the walls of the latter being of a contour suitable for guiding the point of the picker in its desired path, which is represented in the several figures of the drawings 75 by dotted lines adjacent to the points of the pickers. The movable side 19 of the motor-bellows is normally held in its open position (shown in Fig. 1) by means of a spring s, and the interior of each bellows communicates by means of the tubes 20 with suitable devices for exhausting the air therefrom at the desired intervals for operating their respective pickers.

The foregoing brief description applies to 85 the features of this class of instruments which are already well-known in the art. I will now describe the improved means of my present invention by which the pickers are caused to follow the contour of their respective guiding-cams as they are reciprocated longitudinally by means of their respective motor-bellows.

In order to adapt the pickers to engage 90 properly with the controllers of the present invention, they are each provided with an arm 30, which may be removably attached to the picker, as shown in Figs. 3 and 4, or be integral therewith, as in Fig. 5. This arm extends from the picker substantially at right 95 angles to the general direction of its longitudinal movement and radially from the point

of its pivotal connection with its motor-bellows.

The controller 32 is attached to the harp or to any convenient fixed portion of the instrument and engages with the arm 30 of the picker at a suitable distance from the plane of movement of the picker-pivot for causing the desired lateral movements of the picker. The engaging surface of the picker or of the controller, or both, are preferably faced at ⁵ f with leather or other material suitable for causing the desired friction and for insuring the silent operation of the parts. The controller is either resilient in itself, as indicated in Figs. 3 to 7, inclusive; or is provided with means, as a spring, for pressing its picker-arm-engaging surface resiliently into contact therewith, as in Figs. 8 to 10, inclusive. In the form shown in Figs. 3 and 4 the controller consists of a resilient plate which is attached by means of the screws 33 to the harp 15, the tension, and consequently the force of its frictional engagement with the picker-arm, being varied by means of the adjusting-screw 34.

In the modification shown in Fig. 5 the picker-arm 30^a is shown to be integral with the picker 17, extending from its pivotal connection with the motor-bellows at right angles ³⁰ to the picker, through a slot in the harp, to the plane of its engagement with the controller 32^a, which presses against the side of the arm instead of against the end thereof, as in the previous figures. On account of this sidewise pressure the jointed connection of the picker with the motor-bellows should be extended, as shown in Figs. 6 and 7, the picker being provided with a hub 31 of suitable length to counteract the sidewise pressure of ³⁵ the controller.

In the modification shown in Figs. 8 and 9 the controller 32^b is composed of two members which are pivotally mounted upon the harp and engage upon opposite sides of the picker-arm 30^b, the amount of pressure and the consequent friction being determined by ⁴⁰ the tension of the spring 38.

In the modification shown in Fig. 10 the controller 32^c is a single member pivotally mounted upon the harp 15 and pressed into ⁵⁰ engagement with the end of the picker-arm 30^c, the amount of pressure and consequent friction being determined by the tension of the spring 38^c.

I claim as my invention— ⁵⁵

1. In a stringed musical instrument, a pivotally-mounted reciprocating picker and a controller for frictionally engaging with the picker at one side of the plane of movement of the pivot thereof, for oscillating the picker ⁶⁰ in one direction during its forward movement and in the opposite direction during its backward movement.

2. In a stringed musical instrument, a pivotally-mounted reciprocating picker, a guiding-cam therefor, and a controller frictionally engaging with the picker at one side of the plane of movement of its pivot, whereby the picker is caused to follow the contour of the guiding-cam during its reciprocations. ⁶⁵

3. In a stringed musical instrument, a pivotally-mounted reciprocating picker, a guiding-cam therefor, a controller, and means for resiliently pressing the controller into frictional engagement with the picker, at one ⁷⁰ side of the plane of movement of its pivot to hold the picker laterally into contact with its guiding-cam during its reciprocations.

4. In a stringed musical instrument, a pivotally-mounted reciprocating picker, a guiding-cam therefor, and a controller resiliently pressed into frictional engagement with the picker, at one side of the plane of movement of its pivot, for holding the picker laterally in contact with its guiding-cam during its ⁷⁵ reciprocations, with means for varying the intensity of the resilient frictional engagement of the controller with the picker.

Signed by me, at New York city, this 29th day of March, 1898.

WALFRID GUSTAFSON.
